US00D871357S

(12) **United States Design Patent** (10) Patent No.: **US D871,357 S**
 Rock et al. (45) Date of Patent: **** Dec. 31, 2019**

(54) **SERRATED LIGHT ENGINE AND CIRCUIT BOARD**

(71) Applicants: **Ty Rock**, Beverly, MA (US); **Chaim Becerra**, Danvers, MA (US); **Biju Antony**, Lynnfield, MA (US)

(72) Inventors: **Ty Rock**, Beverly, MA (US); **Chaim Becerra**, Danvers, MA (US); **Biju Antony**, Lynnfield, MA (US)

(73) Assignee: **Osram Sylvania Inc.**, Wilmington, MA (US)

(**) Term: **15 Years**

(21) Appl. No.: **29/665,331**

(22) Filed: **Oct. 2, 2018**

CLAIM

The ornamental design for a serrated light engine and circuit board, as shown and described.

DESCRIPTION

FIG. 1 is a top plan view of a first embodiment of a serrated light engine and circuit board, showing our new design;

FIG. 2 is a left side perspective view thereof;

FIG. 3 is a right side perspective view thereof;

FIG. 4 is a left side view thereof;

FIG. 5 is a front view thereof;

FIG. 6 is a top plan view of a second embodiment of a serrated light engine and circuit board, showing our new design;

FIG. 7 is a left side perspective view thereof; and,

FIG. 8 is a right side perspective view thereof.

All surfaces not shown form no part of the claimed design.

1 Claim, 8 Drawing Sheets
